UNITED STATES PATENT OFFICE.

WILLIAM H. HARRIS, OF BOSTON, MASSACHUSETTS.

PROCESS OF AND APPARATUS FOR GENERATING GAS.

SPECIFICATION forming part of Letters Patent No. 463,965, dated November 24, 1891.

Application filed April 30, 1891. Serial No. 391,111. (No model.)

To all whom it may concern:

Be it known that I, WILLIAM H. HARRIS, a citizen of the United States, and a resident of Boston, in the county of Suffolk and State 5 of Massachusetts, have invented certain new and useful Improvements in Processes of and Apparatus for Generating Gas, of which the following is a specification.

The object of my invention is, first, to generate gas from bituminous coal and steam and air supplied thereto to promote combustion, the products of which are suitably mixed and form a fuel-gas or low-illuminating gas.

Another object of my invention is to enrich said gas to any desired degree suitable for illuminating purposes by adding to the fuel-gas hydrocarbon, which is also converted into gas in the process.

Another object of my invention is to provide means for carrying on said process in the best manner, all of which will be fully set forth in the description of the accompanying drawings, making a part of this specification, in which—

25 Figure 1 is a side elevation of my improved generator. Fig. 2 is a central vertical section of Fig. 1. Fig. 3 is a section on line $x-x$, Fig. 2. Fig. 4 is a section on line $y-y$, Fig. 2.

In Fig. 2 I have shown a section representing the preferred form of construction.

30 A represents the base of the retort or generator.

B represents the structure forming the generating-chamber.

35 C represents the generator-hearth, which is made of fire-brick or other similar refractory substance.

1 represents the generating-chamber. The coal is preferably fed in at the top of this 40 chamber, which is kept gas-tight by the following instrumentalities:

45 2 represents a bell, which is suspended upon a chain 3 over the drum 4, which is operated by means of the hand-wheel 5 (see Fig. 1) to lower the bell sufficiently to allow coal to be fed in the ordinary manner.

50 6 represents a water-chilled collar on the crown-seat 7. I prefer to employ no grate-bars, but to remove ashes through a chute 8, which is closed by the ordinary sealed door. The air for promoting combustion is supplied through a series of tuyeres D by means of a

pump or fan. In order to prevent the bridging of the mass of fuel and the formation of clinkers, I mingle with this air a small quantity of steam, which is supplied by means of a series of steam-pipes E, having a connection F with each of said tuyeres.

G represents valves for regulating the supply of steam.

H represents valves for regulating the supply of air.

H' represents an air-blow-off valve.

The generator is kept supplied with a sufficient body of coal and a requisite quantity 65 of air to maintain incandescence of the bottom portion of the charge, and the upper portion is maintained at a glowing heat. The charge of coal preferably reaches to about the point 10, but a small distance below the 70 steam-pipe 11, preferably from three to four inches. By reason of this large body of coal and a small body of incandescence the incandescent gases generated are caused to pass through the heated body of coal above, so as 75 to be enriched by the carbon in the body of the charge and by the hydrogen of the steam which is introduced at the base with air to form the blast. Only a sufficient quantity of steam should be introduced through the 80 tuyeres to prevent clinkering and not enough to deaden or slacken the combustion.

11 represents a steam-pipe for supplying additional quantity of hydrogen and oxygen. This steam is superheated by passing through 85 a coil of pipe 12, which surrounds the upper end of the generating-chamber.

13 represents a valve for regulating the quantity of superheated steam admitted above the charge of coal. The steam thus admitted 90 strikes the bricks, but does not strike the coal or coke at the top of the charge, and does not slacken the combustion or generation of gases to nearly so great a degree as when it strikes the glowing coal or coke, because the charge 95 of coal is not incrusted and the bricks retain a greater amount of heat than the same area of coke, and because the glowing mass continues to give off its heat to the superheated steam introduced above the mass and to the 100 walls of the generator. These gases are carried off by the uptake-flue 14. In order to thoroughly mix these gases and convert them into a fixed form, it is necessary that they be

retained under a high heat for a considerable length of time and subjected to frictional resistance, which will cause a thorough mingling of the currents while in a heated condition, commonly called "regenerating." For this purpose I provide a continuous regenerating-chamber J, preferably of the serpentine form, as shown in Fig. 2, filled with a series of balls I, which are composed of refractory material capable of resisting a long continuous high heat, such as silicate of alumina or material from which fire-brick is made. I have found by experience that when the regenerative agents are formed of brick or other plain-faced objects there is a much greater tendency for the deposition of carbon than when the substances are made round, so as to not form pockets, but curvilinear flues or passages. In order to present as much heating-surface as possible, these balls I are made round and of different sizes, as shown; but they may all be of the same size. The gas and products of combustion are caused to pass through these series of serpentine chambers and to discharge through the flue L into a condenser for cooling, whence the gases are taken and washed and purified in the usual manner.

If it is desired to form an illuminating-gas, it is necessary to enrich the gas generated in the generating-chamber 1, and this is accomplished, preferably, by introducing crude oil or other hydrocarbon through pipe N into the regenerating-chamber, so that any desired degree of richness of illuminating-gas may be obtained.

M represents a graduated oil-feed.

O represents a valve for regulating the flow into the regenerating-chamber.

P represents a supply-pipe, which connects with the tank or pump.

r represents a pipe conveying steam from the coil 12, which heats the hydrocarbon and assists in forcing it into the generating-chamber.

Q represents a blow-off pipe, which connects with the water-chamber a of the water-chilled collar 6.

b represents a water-supply pipe, and c a water-escape for supplying said water-collar.

It is necessary in the starting up of this apparatus to raise the regenerating-chamber and the regenerative balls to a high degree of heat before the gas can be saved for consumption. At the initial starting there is a deposition of carbon in the regenerating-chamber which must be removed. I accomplish this by supplying air and converting said carbon into a gas by combustion. This I accomplish by means of air-supply pipes d. (Shown in Figs. 1, 3, and 4.) e represents valves for opening and closing said tuyere-pipes. In Fig. 4 I have shown two of these air-supply pipes, one tapping into the chamber or the passage f and the other into the chamber or passage g. In the alternate chambers I provide blow-off pipes h, which are shown in dotted lines,

Fig. 4, provided with regulating-valves i, so that when the valves e and i are open the air enters through the pipes d, passes through the regenerating-chamber, ignites the carbon, and the products of combustion escape through the blow-off pipes h. This operation of igniting and blowing off the carbon must be continued until the regenerating-chambers and balls are raised to a sufficient heat to prevent the accumulation of carbon deposits, so that the entire product of gas generated in the generator is also subject to contact with the mass of balls in the regenerating-chambers, which causes a thorough reunion of these gases and a formation of fixed oxyhydrocarbon gases.

I have found that by maintaining a large mass of fuel in the generating-chamber, kept at a glowing heat, through which the gases produced by the incandescence are caused to pass and mingle with the gases generated from the mass of coal above the point of incandescence, and by the admission of steam above the glowing mass without addition of hydrocarbon a good fuel-gas can be formed, and by admitting hydrocarbon in the generating-chamber, which is united with the gases generated from the coal and steam, a good illuminating-gas is produced.

Mode of operation: Kindling is placed upon the hearth of the generator and ignited, the bell is lowered, and a small amount of coal fed in until there is a sufficient body, when more coal is added and the blast started. The bell is then raised to form a seal, and the air and blow-off pipes d and h are opened occasionally to force combustion in the regenerating-chamber, which is continued at intervals until the said regenerating-chamber is raised approximately to a white heat, when the plant is in condition for the generation of gas for storage.

I have shown pipe N for conveying hydrocarbon tapping the regenerating-chamber, and I accomplish important results by supplying hydrocarbon at this point. The supply-pipe does not become unduly heated, and consequently the hydrocarbon is introduced in a liquid form. If said pipe should be placed so as to become unduly heated before tapping the regenerating-chamber, the hydrocarbon would be decomposed and carbon deposited in the end of the pipe, which would clog up the same; but by introducing the hydrocarbon in the manner herein shown no appreciable deposits of carbon are obtained in the pipe.

It will be observed that the regenerating-chamber has a pitch or lean forward from the point where the hydrocarbon is admitted, so that in case it is not all immediately volatilized it will pass down the regenerating-chamber and be mixed with the other gases as it is volatilized.

An important result is accomplished by the process herein described. All the heat produced by the incandescence of the fuel is

utilized not only in the generation of gases but is also imparted to said gases, which in turn impart the same to the regenerating-chamber and its agents, so that a continuous process of generating gas from coal and superheated steam and regenerating the same is carried on, and all the volatile products of combustion are utilized by being converted into gas. The ordinarily non-volatile parts of the coal are rendered volatile by being raised to a point of incandescence in the charge, and as a major portion of the steam enters to enrich the gas impinged against the heated wall in the generator above the body of the coal the fire is not slackened, and consequently a much higher degree of heat is maintained within the generator than in other forms of generators hitherto employed, and the gases are passed into the regenerating-chamber at a higher degree of heat. The steam introduced above the charge being superheated enters with great velocity and assists the draft without deadening or slackening the heat in the generator. Consequently the regenerating-chamber can be used continuously for fixing gas without the necessity of employing two regenerating-chambers and using them alternately.

Having described my invention, what I claim is—

1. The combination of a gas-generator, a series of tuyeres and steam and air supply pipes tapping the generator and discharging thereinto beneath the charge of coal, a coiled superheating steam-pipe surrounding the upper part of said generator and discharging therein above the body of coal, a regenerator having a serpentine passage forming a series of chambers connected by curved ends or passages, air-supply pipes and blow-off pipes connected with the alternate chambers or passages of said regenerator, and a valved pipe for introducing hydrocarbon into the regenerator near the passage through which it communicates with the gas-generator, substantially as described.

2. A gas-generator consisting of a generating-chamber having a solid hearth, a series of air and steam supply pipes tapping the generator near the base of the charge, a steam-pipe coiled round the top of the generator and piercing the same above the body of coal in the generator, whereby the steam is im-

pinged against the walls of the generator above the coal, and the flue 14 for conducting the products of combustion to a regenerating-chamber, substantially as specified.

3. A gas-generator composed substantially of the generating-chamber having the solid hearth, the series of air and steam supply pipes piercing the chamber at its base, a coil of superheating-steam pipes surrounding the top of the generating-chamber and piercing the same above the charge, the take-up flue 14, a continuous regenerating-chamber, and an oil-supply pipe piercing the walls of the regenerating-chamber, substantially as specified.

4. The process of generating gas in a single generator and fixing-chamber, which consists in subjecting a body of coal to a combined blast of air and steam and burning the same, raising the body of coal to a point of incandescence, continuing the blast of air and steam and intermittently introducing coal and at the same time and continuously introducing other steam just above the charge of coal, thereby thoroughly intermingling the gases and steam in the generator, and then fixing the combined gases by passing them through a fixing-chamber maintained in a highly-heated condition by these said heated products of combustion, which are converted into a fixed gas, whereby the products of combustion are continually passing in a single direction from the generator through the fixing-chamber in a continuous process, substantially as described.

5. In combination with a generator having air-supply pipes piercing its base portion for supporting combustion of soft coal, a steam-supply pipe injecting steam into the generator above the body of burning coal, a continuous regenerating-chamber filled with refractory material packed within the same, forming a series of gas-passages, and one or more air-supply pipes D and blow-off pipes H, tapping the regenerating-chamber, substantially as specified.

In testimony whereof I have hereunto set my hand.

WILLIAM H. HARRIS.
